US00D799023S

(12) **United States Design Patent** (10) **Patent No.:** **US D799,023 S**
Haaf et al. (45) **Date of Patent:** **** Oct. 3, 2017**

(54) **VENTILATION GRID**

(71) Applicant: **ebm-papst Mulfingen GmbH & Co. KG**, Mulfingen (DE)

(72) Inventors: **Oliver Haaf**, Kupferzell (DE); **Thorsten Pisarczyk**, Gemmingen (DE); **Sven Beck**, Krautheim (DE); **Christian Weiss**, Mulfingen-Jagstberg (DE)

(73) Assignee: **EBM-PAPST MULFINGEN GMBH & CO. KG**, Mulfingen (DE)

(**) Term: **15 Years**

(21) Appl. No.: **29/565,985**

(22) Filed: **May 26, 2016**

Related U.S. Application Data

(62) Division of application No. 29/517,203, filed on Feb. 11, 2015, now Pat. No. Des. 775,321.
